UNITED STATES PATENT OFFICE.

ANDERSON W. LUCAS, OF WAVERLY, TENNESSEE, ASSIGNOR TO THEO. F. LUCAS, OF WAVERLY, TENNESSEE.

FIRE-KINDLER.

1,199,999.

Specification of Letters Patent.

Patented Oct. 3, 1916.

Application filed November 18, 1915. Serial No. 62,199.

To all whom it may concern:

Be it known that I, ANDERSON W. LUCAS, a citizen of the United States of America, and a resident of Waverly, Tennessee, have invented a new and useful Improvement in Fire-Kindlers, which invention is fully set forth in the following specification.

This invention relates especially to fire-kindlers adapted to be bodily inserted into a stove, grate or furnace with other fuel, and upon being ignited, to transmit the combustion to the other fuel, the kindler itself being entirely consumed.

The object of the invention is to provide a fire-kindler of this sort which is not only effective in its action, but which is also capable of being cheaply manufactured principally from materials which would otherwise be waste.

In the accompanying drawing, I have illustrated three embodiments of the invention, but it will be understood that the invention is not limited to the exact forms shown, the scope of the invention being defined by the appended claims.

Of the drawings, Figure 1 is a perspective view showing one embodiment of the invention; Fig. 2 is a perspective view showing another embodiment of the invention; Fig. 3 is a perspective view showing still another embodiment of the invention; Fig. 4 is a view showing in detail the shavings of which the fire-kindlers are principally constructed.

Referring to the drawings, especially Fig. 1, the fire-kindler as a whole is represented by 1, the kindler being preferably cylindrical in shape as shown, although this exact form is not essential. The length of the kindler is preferably considerably greater than any other dimension, such as the diameter, thus adapting it to be easily handled and easily inserted into a stove, grate or furnace with other fuel when required.

The kindler comprises a bundle of long shred-like wood-shavings 2, which are matted together and interlaced, the shavings being preferably arranged in the main longitudinally of the bundle. The matted and interlaced shavings are compressed into the shape shown, to form a mass of substantially uniform density throughout. In constructing the kindler, use can advantageously be made of the shavings that are formed in the turning of spokes for wagon and auto-

mobile wheels, these shavings being long and splinter-like or shred-like in character and quite different from the common planing-mill shavings which are merely short brittle chips. The shavings, because of their long shred-like character, become matted and interlaced together and entangled in such a way that they cohere with considerable tenacity, strongly resisting any force tending to pull a mass of them apart. Ordinary shavings would not mat and entangle in the way described.

The shavings are compressed as aforesaid into a suitable bundle, preferably cylindrical as shown, and, while compressed, a suitable binding means is applied, the binding means being combustible so that it will be destroyed when the bundle is ignited. The kindler 1 shown in Fig. 1 has binding means in the form of separated circumferential cords 3 without any connection between them.

The kindler 1^a shown in Fig. 2 has binding means consisting of a cord arrangement in which there are not only cord-sections 3^a—3^a extending around the bundle, but also cord-sections 3^b—3^b extending longitudinally of the bundle between the several sections 3^a. Preferably there is also a cord-section 3^c extending around one end of the bundle. Preferably, as shown in Fig. 2, the several cord-sections, 3^a, 3^b and 3^c are formed of a single piece of cord arranged as shown.

In Fig. 3, there is shown a kindler 1^b which differs from the kindlers shown in Figs. 1 and 2 in that the binding means consists primarily of combustible paper extending circumferentially around the bundle. Preferably, the paper is in the form of a relatively narrow strip 3^b wound spirally so that the strip at 90 each turn overlaps the edge of the preceding turn. The overlapped edges of the paper may, if desired, be glued, as indicated at 4. When unusual strength is required, a combustible cord 5 may be spirally wound around the bundle, so as to lie between the overlapped edges of the paper and to be held by the glue at 4. The cord 5, when used, makes it possible to use a lighter and cheaper paper than would otherwise be necessary.

The binding means serves to maintain the bundle in its initial shape, to prevent its opening while awaiting use. As before stated, the binding means is combustible, and the result is that, when the bundle is 110

ignited, the binding means is destroyed, thus releasing the compressive force on the bundle and allowing it to open or expand because of the elasticity of the shavings, thus admitting air to the interior of the bundle and facilitating rapid combustion.

Either before or after being placed in the bundle, the shavings are impregnated with oil or other substance adapted to add to the 10 inflammability of the kindler.

It will be understood from the foregoing description that the kindlers are relatively small in size, a length of about nine inches and a diameter of about two and a half 15 inches being suitable for the majority of cases. When the kindler is to be used, it is inserted bodily into the stove, grate or furnace and the other fuel to be ignited is placed around it. When a sufficient quantity 20 is in place, the kindler is ignited by any suitable means and burns rapidly. Very soon after ignition, the binding means, which may be either cord or paper, or both, as already described, is burned so as to release the compressive force on the bundle. The elasticity of the shavings is such as to immediately cause expansion of the bundle after the releasing of the compressive 25 force. This expansion permits the free 30 flow of air into the interior of the bundle, thus facilitating and maintaining the rapid combustion. Because of the rapid combustion which is made possible by the peculiar construction that I provide, intense heat is 35 developed which quickly and surely ignites the other fuel.

What is claimed is:—

1. A fire-kindler having its length considerably greater than its other dimensions 40 and comprising in combination a compressed bundle of long shred-like matted and interlaced wood shavings, and flexible combustible binding means under tension and extending circumferentially around the 45 bundle, and being at all points along its inner side in engagement with the bundle and at all points along its outer side exposed to the atmosphere, the said kindler being adapted to be bodily inserted into a 50 stove, grate or furnace and ignited and being automatically expansible when the binding means is burned following ignition thus permitting the shavings to separate and burn to the best advantage.

55 2. A fire-kindler having its length considerably greater than its other dimensions and comprising in combination a compressed bundle of long shred-like oil-impregnated matted and interlaced wood 60 shavings, and flexible combustible binding means under tension and extending circumferentially around the bundle, and being at all points along its inner side in engagement with the bundle and at all points along its 65 outer side exposed to the atmosphere, the

said kindler being adapted to be bodily inserted into a stove, grate or furnace and ignited and being automatically expansible when the binding means is burned following ignition thus permitting the shavings to separate and burn to the best advantage. 70

3. A fire-kindler comprising in combination a compressed uniformly dense cylindrical bundle of long shred-like matted and interlaced wood shavings, and flexible combustible binding means under tension and extending circumferentially around the bundle, and being at all points along its inner side in engagement with the bundle and at all points along its outer side exposed to the atmosphere, the said kindler being adapted to be bodily inserted into a 75 stove, grate or furnace and ignited. 80

4. A fire-kindler comprising in combination a compressed bundle of long shred-like wood shavings chiefly longitudinally arranged, and flexible combustible binding means under tension and extending circumferentially around the bundle, and being at all points along its inner side in engagement 85 with the bundle and at all points along its outer side exposed to the atmosphere, the said kindler being adapted to be bodily inserted into a stove, grate or furnace and ignited and being automatically expansible 90 when the binding means is burned following ignition thus permitting the shavings to separate and burn to the best advantage. 95

5. A fire-kindler comprising in combination a compressed cylindrical bundle of long shred-like matted and interlaced wood shavings, and combustible paper under tension and extending circumferentially around the bundle to bind it, the said kindler being adapted to be bodily inserted into a stove, 100 grate or furnace and ignited and being automatically expansible when the paper is burned following ignition thus permitting the shavings to separate and burn to the best advantage. 105

6. A fire-kindler having its length considerably greater than its other dimensions and comprising in combination a compressed bundle of long shred-like matted and interlaced wood shavings, and a combustible binding cord under tension extending around the bundle, the said cord throughout its length closely following the surface of the bundle and conforming thereto, the said kindler being adapted to be 110 bodily inserted into a stove, grate or furnace and ignited and being automatically expansible when the cord is burned following ignition thus permitting the shavings to separate and burn to the best advantage. 115

7. A fire-kindler comprising in combination a compressed cylindrical bundle of long shred-like matted and interlaced wood shavings, a combustible binding cord under tension extending around the bundle, and 120

combustible binding paper also under tension and also extending around the bundle, the said cord and the said paper closely following the surface of the bundle and serving to hold the bundle compressed, and the said kindler being adapted to be bodily inserted into a stove, grate or furnace and ignited.

8. A fire-kindler comprising in combination a compressed cylindrical bundle of long shred-like matted and interlaced wood shavings, and a strip of combustible binding paper under tension spirally wound around the bundle and serving to hold it compressed.

9. A fire-kindler comprising in combination a compressed cylindrical bundle of long shred-like matted and interlaced wood shav-

ings, and a strip of combustible binding paper under tension spirally wound around 20 the bundle with each turn overlapping the edge of the preceding one, the said paper serving to hold the bundle compressed.

10. A fire-kindler comprising in combination a compressed cylindrical bundle of long 25 shred-like matted and interlaced wood shavings, a strip of combustible binding paper spirally wound around the bundle with each turn overlapping the edge of the preceding one, and a combustible cord spirally wound 30 around the bundle and positioned between the overlapped edge of the strip of paper.

In testimony whereof I have signed this specification.

ANDERSON W. LUCAS.
